UNITED STATES PATENT OFFICE.

WILLIAM ROBERTSON, OF CHICAGO, ILLINOIS.

ELEVATOR FOR CINDER-PITS, &c.

SPECIFICATION forming part of Letters Patent No. 696,491, dated April 1, 1902.

Application filed March 21, 1901. Serial No. 52,150. (No model.)

To all whom it may concern:

Be it known that I, WILLIAM ROBERTSON, a citizen of the United States, and a resident of Chicago, in the county of Cook and State 5 of Illinois, have invented certain new and useful Improvements in Elevators for Cinder-Pits or the Like; and I do hereby declare that the following is a full, clear, and exact description thereof, reference being had to the accompanying drawings, and to the letters of reference marked thereon, which form a part of this specification.

This invention relates to improvements in elevators for cinder-pits or the like, and while 15 shown in a form more particularly designed for use in elevating cinders is obviously adapted for many uses other than the removal of cinders from cinder-pits, the invention being equally applicable to the elevation or trans- 20 portation of any desired material to a place of deposit.

The object of this invention is to provide a simple device easily operated and easily installed and adapted to convey the cinders or 25 other material from the pit or other place where such material normally accumulates to a distance therefrom, where the same is automatically dumped at a place of deposit or into a receiving-car.

30 The invention consists of the matters hereinafter described, and more fully pointed out and defined in the appended claims.

In the drawings, Figure 1 is a front elevation, partly broken, of a device embodying 35 my invention. Fig. 2 is a section taken on line 2 2 of Fig. 1. Fig. 3 is a top plan view of the same. Fig. 4 is a bottom plan view of the same. Fig. 5 is a section taken on line 5 5 of Fig. 4. Fig. 6 is a side elevation of a 40 slightly-modified form of elevator-car. Fig. 7 is a section taken on line 7 7 of Fig. 3.

In carrying out my invention a cinder-pit (indicated by A) is provided with a trans- 45 verse passage opening beneath the track- rail and leading thereunto, (indicated by a.) Track-rails B B', horizontal in the bottom of the cinder-pit, curve to an inclined position at right angles with the main track, as indicated in Figs. 1 and 3, and transversely of 50 the track (indicated by C) which, as shown, is at a lower level than the main track. A

cinder-car C' is shown in Fig. 1, on said track C, below the elevated ends of the track-rails B B'. Intermediate of the rails B and B' is the rail b, which extends transversely of the 55 pit and to a point above the cinder-car, where the end thereof is turned downwardly, as indicated in Fig. 1.

D indicates the cinder-elevator car. Said cinder-elevator car has, as shown, a length 60 approximately equal to the width between the track-rails of the main track, and may be of any desired width and is provided with trucks designed to run on the track-rails B B'. The bottom D' of said car in the form illus- 65 trated in Figs. 1, 4, and 5 is hinged at the rear end of the car and is provided in a median line, longitudinally thereof, with a plu- 70 rality of rollers d d' d'', journaled thereon, as indicated in Figs. 4 and 5, of which the rollers d and d'' are located near each end of the car, while the roller d' is located back of the middle of the car. Said rollers each normally engage the central rail b, whereby the bottom 75 of the car is held in its closed position, as in- 80 dicated in full lines in Fig. 4. Obviously said elevator-car may be constructed of any desired material and may be of any desired shape or size. As shown, however, the sides 85 of the same are constructed of a wire-net- 90 ting or other material provided with apertures therethrough. Any desired or pre- 95 ferred means may be used for actuating said elevator-car. As shown, however, and con- 100 veniently when the device is installed at a round-house or power-station, the same is ac- tuated by compressed air, as follows: E in- 105 dicates a supporting-frame upon which the outer ends of the track-rails B and B' rest at any desired height or angle of inclination 90 with the ground. Located beneath the same, as shown vertically, is the cylinder F, which may be of any desired length. Said cylinder is provided with a piston-head, (indicated in dotted lines in Fig. 1,) having a piston-rod f 95 connected therewith, provided at its upper end with a sheave. The upper end of the piston-rod when the piston-head is at the upper end of said cylinder extends to near the top of said frame E.

F' indicates an air-pipe communicating with the cylinder at the upper end thereof

and extending upwardly and along the rail B' into close proximity with the side of the cinder-pit, where the same is connected with a pipe f², leading to any convenient source 5 of supplying air under pressure, such as is commonly found at round-houses or the like, comprising a drum containing air under pressure. An operating-valve f³ is connected in said pipe adjacent to the cinder-pit, in position to be actuated by an operator standing 10 near the pit. A line or other flexible connection leads from the front of the car through a sheave e, secured on the top of said frame, through the sheave on the upper 15 end of the piston-rod f, and is secured on said frame, so that when the piston-rod is moved downwardly the line is pulled downwardly therewith, thereby pulling the car along the track into dumping position.

20 The operation is as follows: The elevator-car having been filled and it being desired to dump the same into the receiving-car C', the valve f³ is actuated, thereby admitting air to the cylinder F and forcing the piston 25 downwardly. This draws the bight of the line downwardly sufficient for the car to assume the position shown in dotted lines in Fig. 1. When the roller or truck d reaches the curved portion of the center rail b, the bottom 30 of the car opens downwardly, as indicated, and the load supported thereon slides into the receiving-car C', said bottom of the car being at that time supported on the curved end of the rail b by the truck or roller d'.

35 The load having been deposited, the air is permitted to escape from the top of said cylinder through the valve f³ or otherwise, whereupon the car moves downwardly, the weight thereof serving to lift the piston sufficiently to permit the elevator-car to return 40 to its filling position in the cinder-pit. As said car moves down the track the truck d' glides upwardly over the curved end of the rail b, thereby lifting the bottom D' until the 45 truck d engages and serves over said curved portion, with the effect of entirely closing the bottom. Obviously it is not essential that the car D be constructed with a one-piece bottom. Fig. 6 illustrates a car in which the 50 bottom consists of two oppositely-hinged sections of unequal width, each provided with a roller at the inner end and at the outer end. The longer bottom-section is hinged at the rear end of the car. Toggle-arms d³ are attached to each section adjacent to the meeting edges thereof, with the connected ends 55 projecting upwardly within the car. When said car is in the dumping position, the bottom assumes the position indicated in dotted 60 lines in Fig. 6, with the front roller of the larger bottom-section supported on the curved portion of the rail b. (Also shown in dotted lines.) The car having dumped, the rearward movement of the elevator-car causes 65 the front end of the larger section to move upwardly as the roller serves over the same, the shorter section being also pushed up-

wardly by the toggle-arms, thus closing the car-bottom when all of said rollers are supported upon the rail b, as before described. 70

Obviously a device embodying my invention can be used for many purposes besides elevating cinders from a cinder-pit, and a very convenient use may be found in excavating. The same may be employed, if preferred, with 75 a steam-shovel whenever it may be desirable to dump the material excavated by the shovel at a distance from the excavation. If preferred, other means than compressed air may be used to actuate the car. So, too, if preferred, a car may be constructed having a plurality of movable or hinged sections pivoted along its length, supported normally upon a rail or rails, which hold the same in their closed position, and, obviously, many 80 details of construction may be modified without departing from the principle of my invention.

I claim as my invention—

1. A car provided with a downwardly-operating bottom hinged at one end thereof, a plurality of rollers journaled centrally on said bottom and adapted to normally engage a supporting-rail acting to hold said bottom in a closed position. 90

2. A car comprising apertured side walls, a downwardly-opening bottom hinged at one end thereof, a plurality of rollers journaled centrally on said bottom and adapted to normally engage an immovable support acting to 100 hold said bottom in a closed position. 95

3. In a device of the class described, the combination with a car having rigid side and end walls of a downwardly-opening bottom hinged at the rear end thereof, a plurality of 105 rollers disposed on said bottom centrally and longitudinally thereof, a track on which the car is supported, a relatively short rail intermediate of the track-rail upon which said rollers engage and which acts to support said bottom in a closed position said track being curved from a horizontal to an inclined position, a downwardly-turned portion at the outer extremity of the said intermediate rail at which point the bottom of said car opens 110 and permits the contents of said car to slide outwardly. 115

4. The combination in a pit-elevator of an inclined track leading from the pit, a track beneath the outer end of said inclined track 120 adapted to support a receiving-car, an elevator-car movable along said inclined track, rigid side and end walls on said car, a downwardly-open bottom hinged at its rear end to the rear end of the car, an intermediate rail 125 terminating in a downward end above the receiving-car, rollers disposed longitudinally on the bottom of the elevator-car and adapted to engage said intermediate rail, said rollers being so disposed that one or more of the same 130 remain at all times in engagement with the intermediate rail and means for moving the elevator-car along its track to dumping position. 135

5. In a device of the class described, the combination with a railway cinder-pit of a transverse passage opening thereto, inclined track-rails extending transversely upwardly and outwardly from the cinder-pit, an elevator-car thereon, apertured side walls on said car, a downwardly-opening bottom hinged at the rear end of the car, rollers disposed longitudinally thereon, a relatively short rail located between said transverse track-rails and adapted normally to be engaged by said rollers and to support said bottom in its closed position thereby, the outer end of said intermediate rail being downwardly curved, means operated by pneumatic pressure for moving the car outwardly and upwardly from the cinder-pit to a dumping position at the end of said intermediate rail at which point the bottom of said car drops downwardly with one of the rollers thereof still engaging said rail. 15 20

In testimony whereof I have hereunto subscribed my name in the presence of two subscribing witnesses.

WILLIAM ROBERTSON.
